United States Patent Office

Des. 180,574

Patented July 9, 1957

180,574

CAMERA

Melvin H. Best, Pasadena, and Robert S. Inlow, Los Angeles, Calif., assignors to Karl Freund, San Fernando, Calif.

Application July 19, 1956, Serial No. 42,293

Term of patent 14 years

(Cl. D61—1)

Fig. 1.

Fig. 2.

Fig. 3.

Fig. 1 is a front view of a camera showing our new design.

Fig. 2 is a top view of Fig. 1.

Fig. 3 is a rear view thereof.

Fig. 4 is a side view thereof taken from the right of Fig. 1.

Fig. 5 is a side view thereof taken from the left of Fig. 1.

Fig. 6 is a front perspective view thereof with the lens door in open position.

We claim:

The ornamental design for a camera, substantially as shown.
